DESIGN FOR A MEDAL

Frank H. Irelan, Dayton, Ohio

Application June 23, 1941, Serial No. 101,628

Term of patent 3½ years

To all whom it may concern:

Be it known that I, Frank H. Irelan, a citizen of the United States, residing at Dayton, in the county of Montgomery and State of Ohio, have invented a new, original, and ornamental Design for a Medal, of which the following is a specification, reference being had to the accompanying drawing, forming part thereof.

In the drawing:

Fig. 1 is a front view of the medal, showing my new design.

Fig. 2 is a rear view of the pendant disc element only.

I claim:

The ornamental design for a medal, as shown.

FRANK H. IRELAN.
